COKING BITUMINOUS MATERIAL

Edmund O. Rhodes, Pittsburgh, Pa., assignor to
The American Tar Products Company, a cor-
poration of Delaware

Application February 9, 1929. Serial No. 338,644

3 Claims. (Cl. 202—17)

My invention relates to the coking of bitumi-
nous materials, either liquid or such as may be
brought into a liquid or mobile condition by heat-
ing, and such, for example, as tar or pitch.

5 An object of my invention is to provide a
process of reducing such materials to coke in ex-
ternally heated coking retort ovens of the by-
product type, for example, those commonly used
for coking coal, whereby certain disadvantages
10 of the prior art may be avoided.

My invention has for further objects such
other operative advantages or results as may
hereinafter be found to obtain.

Numerous attempts have been made in the
15 past to accomplish the coking of tar and pitch in
externally heated coking retort ovens, but such
attempts have been subject to numerous disad-
vantages and difficulties and cannot be regarded
as practical solutions of the problem. Some of
20 these difficulties arose from the liquid nature of
the material and its tendency to foam, which
caused leakage through cracks in the retort walls
and around the doors. Also, the introduction of
the material to be coked in a comparatively large
25 body into a highly heated retort in the manner
of the prior art caused a chilling of the retort
which resulted in the scaling off of the surfaces
so exposed to heating and cooling, and also
caused an undue expansion and contraction of
30 the retort as a whole, the opening of the cracks
between the bricks and the impairment of the
cement, and from one and all of these causes the
retorts were rapidly deteriorated and injured.

On the other hand, when it was attempted to
35 introduce the pitch or other material progres-
sively and slowly into the retort, it was found
that the high temperatures obtaining in the re-
tort caused considerable cracking of the products
of distillation and the formation of excessive
40 amounts of lampblack, an undesirable impurity.

My invention obviates these difficulties and
disadvantages by performing the coking of the
pitch continuously and, at the same time, intro-
ducing into the retort the material to be coked,
45 together with a suitable quantity of superheated
steam or other inert gas. The material to be
coked is introduced in relatively small quantity
at a time into the highly heated retort so that
the chilling effect at any time is so small com-
50 pared with the extent of the retort and the high
heat of the same that the above-described in-
juries cannot result. Nevertheless the pitch is
introduced into the retort with sufficient rapidity
55 so that a batch of substantially pure coke in

quantities equal to the capacity of the retort is
produced without undue expenditure of time.

My invention may be applied to the coking of
substantially any bituminous material that may
be liquefied, or otherwise brought into a mobile
condition, and which is capable of being coked.
However, when tar is to be reduced to coke, it is
60 preferred to subject it to a preliminary distilla-
tion operation to remove its more volatile consti-
tuents and to reduce the bituminous residue to
pitch, without however destroying its essentially
65 liquid nature at the temperature of distillation.

Moreover, by thus first removing the lighter
distillates by ordinary distillation means, a larger
70 total yield of oils is made possible, as cracking of
such light constituents, which would occur if the
entire distillation took place in the coking retort,
is thereby avoided.

When pitch has previously been obtained or
75 prepared and is therefore found in a more or less
solid or even brittle condition at ordinary tem-
peratures, it is necessary to again reduce the pitch
to a mobile condition, for example, by heating it in
order that it may be introduced into the coking
80 retort oven without difficulty.

In any event, the hot mobile material is intro-
duced directly into the coking retort oven in the
85 manner herein described, together with steam or
other inert gas, and in such manner as to prevent
chilling of the material and consequent plugging
of the distributing apparatus due to solidification
of the bituminous material therein.

In order that my invention may be clearly set
forth and understood, I now describe with refer-
ence to the accompanying drawings a preferred
90 manner in which it may be practiced and em-
bodied, but without limiting the claimed inven-
tion specifically to the details of such illustrative
examples. In the drawings,

Figure 1 is a more or less diagrammatic view
95 of apparatus for reducing tar to coke and for
recovering the products of distillation, said appa-
ratus including a portion of a battery of by-
product coking retort ovens of well known type;

Fig. 2 is a vertical sectional view of a horizon-
100 tal coking retort oven provided with means for
accomplishing the coking of bituminous material
according to the present invention; and

Fig. 3 is a view in vertical section of means
for introducing liquid bituminous material and
105 steam or other inert gas into a coking retort oven.

Similar numerals designate similar parts in
each of the several views of the drawings.

Referring to the drawings and especially to
Fig. 1 there is shown at 1 a tank for the storage
110

of tar or similar material which it is desired to reduce to coke. For this purpose there is employed a still 2 for first reducing the tar to pitch, and a coking retort oven 3 for subsequently reducing the pitch or other tarry residue to coke.

The coking retort oven 3 may be one of a plurality of similar coking retort ovens having heating flues 4' in the side walls and forming a battery 4. The remaining ovens 5 of the battery 4 may be employed for the same purpose or for the coking of coal in the usual manner. It is often advantageous thus to employ one or more of the coke ovens of a battery employed primarily for coking coal for the reduction to coke of the tar produced in the coking operation carried on in the remaining ovens.

Sufficient tar is introduced from the tank 1 by means of a pump 7 and a line 8 to fill the still 2 to a predetermined level and the tar in the still 2 is then distilled in the usual manner, by means of burners 9 or other means for applying heat. The products of distillation pass from the still 2 through a vapor line 10 into a condenser 11 where they are condensed by being subjected to a spray 25 of water from a line 12 and pump 13. The mixture of condensed oils and water then passes through a line 14 to a separating tank 15.

By means of the pump 13 and the line 12, a continuous recirculation of water is maintained, 30 enough fresh water being introduced from the make-up water line 16 to keep the temperature of the condensing system sufficiently high to prevent condensation of heavy resinous products of distillation from the retort oven, but low enough 35 to condense the lower boiling distillates, for example, at about 75° C.

Excess water is removed from the separating tank 15 through a line 17 and the condensed oils are drawn by a pump 18 through lines 19 and 20 40 and are pumped into a receiver 21. Fixed gases which do not condense in the condenser 11 escape through a line 23 and are dealt with as will be described hereinbelow.

When the residue remaining within the still 45 2 has attained the desired quality, the tar is pumped into the still 2 at a rate sufficient to maintain the temperature in the still 2 substantially constant, and at the same time pitch is pumped from the still 2 into the coking retort oven 3, 50 which has previously been heated to carbonization temperatures.

By means of a submerged pump 25 within the still 2 and below the surface of the pitch contained therein, pitch is continuously withdrawn 55 from the still 2 through a line 26 in amount considerably larger than is required for the filling of the coking retort oven 3, and this pitch passes through a line 27 having a plurality of offtake valves 28 corresponding to the charging holes in the coking retort oven 3 and the excess pitch returns through a line 29 to the still 2.

In this manner a constant recirculation of pitch through the lines 26, 27 and 29 is provided so that the pitch remains fluid, and chilling and 60 consequent stoppage are prevented. Provision should also be made so that in the event of a cessation of pumping the liquid pitch will drain out of the lines 26, 27 and 29 and return to the still 2.

The valves 28 are illustrated in detail in Fig. 3 and as there shown are so constructed as to offer comparatively little obstruction to the flow of liquid through the line 27. Each valve 28 is provided with an offtake 30 extending down into the coking retort oven 3 through a charging hole 31

thereof and through a suitable opening 32 in the charging hole cover 33, the opening 32 being luted with fireclay as shown.

The offtake 30 is provided with an extension 34 extending into the interior of the valve 28 and terminating in a valve seat 35, the flow of pitch through the extension 34 being regulated by regulating the distance between the valve seat 35 and a corresponding valve member 36. The valve member 36 is conveniently carried by a hollow spindle 37 extending into the interior of the extension 34 and which also passes through a gland 38 and communicates through a valve 40 with a line 41 supplying steam or other inert gas. By means of a hand wheel 42 suitably disposed, the spindle 37 and valve member 36 may be caused to be raised or lowered, thus opening or closing the orifice through which pitch discharges from the line 27 through the offtake 30 into the coking retort oven 3.

A hand wheel 45 is provided which engages the extension 34 and offtake 30 by rotation of which connection between these two may be severed and the offtake 30 thereby withdrawn from the charging hole 31 by means of a suitable handle 46.

The end of the offtake 30 terminating within the coking retort oven 3 is provided with a suitable flare 47 having a relatively long and narrow opening co-axially disposed with the longitudinal axis of the coking retort oven, and whereby a more or less fan shaped spray of liquid is secured which impinges the least possible amount on the walls of the coking retort oven.

The valves 28 are so regulated as to allow a suitable amount of the pitch passing through the line 27 to discharge through the offtakes 30 into the interior of the coking retort oven 3, the rate of flow being so regulated as to accomplish the filling of the retort in the minimum time, without however allowing the coking retort oven 3 to contain a large amount of liquid material at any one time. In short, the introduction of the material to be coked is regulated correspondingly to the progress of solidification of the charge within the coking retort oven 3.

While the introduction of the material is preferably accomplished substantially continuously, this does not preclude such intermittent operation as results from the frequent and regular opening and closing of the valves 28. It has been found that in some instances, particularly where pitch is remelted, there may be some difficulty in keeping relatively small and continuously operating valves open and free, and under such circumstances somewhat larger valves may be used, these valves being operated intermittently. However, the quantities discharged at any one time are comparatively small and the intervals between successive periods are preferably kept very small so that such intermittent charging effects practically the same results as continuous charging and may be regarded as substantially continuous for the purposes of the present specification.

The actual time required to fill the coking retort oven and to complete the coking of the charge will, of course, vary considerably with the size of the oven, the nature of the material charged, the temperatures carried in the heating flues, and the like, and will, in each individual instance, be governed largely by the discretion of the operator. However, in order that this description may be complete, the results of a typical procedure are given below.

A coking retort oven may be employed which

is of standard dimensions, for example, about 40 feet long, about 10 feet high, having an average width of about 16 inches, and comprising a portion of a battery of such ovens, ordinarily 5 employed for coking coal. The tar to be reduced to coke is first distilled in a tank still operated continuously, tar being introduced at such a rate as to maintain the temperature of the charge at a substantially constant temperature. The charging of the coking retort oven in this instance will ordinarily require approximately six hours, the oven being filled to a depth of about 6½ or 7 feet. After filling the oven, the charge is left in the oven for approximately 10 hours to complete the coking operation, after which coke is discharged from the oven by a pushing operation by means of the customary pushing apparatus employed in removing coal coke from by-product coke ovens. The entire 15 operation thus consumes about 16 hours, more or less.

During the shrinking period of about 10 hours the distillation of tar in the still is continued. The level of material within the still rises during this period until, at the conclusion of the shrinking period and after discharge and sealing of the coking retort oven, a sufficient supply has been built up in the still to again fill the oven. This process is repeated as long as is 20 desired.

The extent to which the distillation is carried in the primary still before the tar is discharged into the coking retort oven for coking will depend largely upon the particular conditions involved, but ordinarily I prefer to pre-distill the tar to pitch having a melting point in the neighborhood of 300° F. It is, of course, to be borne in mind that the farther the distillation is carried in the primary stage the smaller 25 the loss of oils due to cracking in the coking stage. On the other hand, as the melting point of the pitch residue rises, the difficulties encountered in handling it and keeping it fluid also increase, and for many purposes it may be 30 desirable to carry the distillation in the primary still to a point where the residue has a considerably lower melting point than those hereinabove specified; for example, from 200° to 250° F. Such melting points are of course determined by the standard methods used in 35 practice.

When the desired quantity of pitch has been accumulated within the coking retort oven 3, the valves 28 and 40 are closed and the offtakes 55 30, if no cooling means, such as steam jackets, are provided, may then be withdrawn from the charging holes 31 to protect them from the high heat subsisting within the latter, and the holes 32 in the charging covers 33 are then luted with 36 clay or similar material to prevent escape of gaseous products of distillation.

The steam and vapors produced by the distillation of the pitch are withdrawn through the usual standpipe 50, but are prevented from 40 passing into the collecting main 51 which serves the remaining ovens of the battery by a suitable valve 52, similar to those generally provided in standpipes, which is kept closed, and instead pass through a vapor line 53 to the condenser 11 where they mingle with the gases coming from the still 2 and are condensed. The incondensable gases then pass through lines 45 23 and 54, having a valve 55, into the collecting main 51 where they mingle with the coal gas produced in the remaining ovens 5, or else pass

through an outlet 56 having a valve 57 to the atmosphere or to whatever use may be desired for them.

Suitable means should be provided for maintaining a proper pressure within the coking retort oven 3, preferably of automatic type. Of course, when the incondensable gases are led into the collecting main 51 serving other coking retort ovens of the battery, the usual pressure regulator serving the other ovens 5 also serves to regulate pressure conditions within the oven 3.

It should be observed that when steam is employed as the inert gas in introducing the bituminous material into the coking retort oven, the incondensable gases produced in the distillation of the pitch contain substantially no inert and may readily be mingled with the gases coming from the remaining ovens 5, but where some other inert gas, such as carbon dioxide or nitrogen, is employed for this purpose, the mixture of incondensable gases and inert gas may ordinarily not be introduced into the coal gas.

After the coking retort oven 3 has been charged with pitch in the manner recited above and the offtakes 30 have been withdrawn, the 100 coking operation is continued until all or nearly all of the volatile matter has been driven off, leaving coke of good quality. This operation generally requires from eight to ten hours when the oven is kept at carbonizing temperatures, depending also upon the size of the oven, and also results in the shrinking of the coked mass within the coking retort oven, which permits discharging the coking retort oven. Thereafter the coke is removed in the usual manner 105 without interrupting the substantially continuous heating of the retort, and after the retort doors have again been closed, the same continuous introduction and coking of a further amount of pitch is proceeded with.

While my invention has been hereinabove described with respect to a certain specific example, it is not limited to such specific embodiment, but may variously be practiced and embodied within the scope of the claims herein-after made.

I claim as my invention:

1. A process of manufacturing coke from bituminous material selected from a group consisting of liquid bituminous material and liquefiable bituminous material in a by-product oven having side walls with heating flues extending substantially through the entire height of the walls, which process comprises heating the side walls of the oven to maintain the coking chamber at coking temperature, spraying into the coking chamber said bituminous material with a gaseous medium substantially free from uncombined oxygen so as to produce a liquid spray which on passing downwardly through the oven 125 is substantially freed of foaming constituents that cause excessive foaming, regulating the feed of the bituminous material in the oven so that the liquid sprayed bituminous material collected in the oven at any time will not cause undue chilling 130 of the walls of the oven, and continuing the coking of collected residual matter to bring about shrinkage thereof to free coke from the side walls of the oven and to form a coke that is removable en masse from the oven by a pushing operation, and pushing the coke out of the oven.
2. A process of manufacturing coke from bituminous material selected from a group consisting of liquid bituminous material and liquefiable bituminous material in a by-product oven hav- 150

ing side walls with heating flues extending substantially through the height of the walls, which process comprises heating the side walls of the oven to maintain the coking chamber at coking temperature, spraying into the coking chamber said bituminous material with steam so as to produce a liquid spray which on passing downwardly through the oven is substantially freed of foaming constituents that cause excessive foaming, regulating the feed of the bituminous material in the oven so that the liquid sprayed bituminous material collected in the oven at any time will not cause undue chilling of the walls of the oven, and continuing the coking of collected residual matter to bring about shrinkage thereof to free coke from the side walls of the oven and to form a coke that is removable en masse from the oven by a pushing operation, and pushing the coke out of the oven.

20 3. A process of manufacturing coke from pitch in a by-product oven having side walls with

heating flues extending substantially through the entire height of the walls, which process comprises heating the side walls of the oven to maintain the coking chamber at coking temperature, spraying into the coking chamber said pitch with a gaseous medium substantially free from uncombined oxygen so as to produce a liquid spray which on passing downwardly through the oven is substantially freed of foaming constituents that cause excessive foaming, regulating the feed of the pitch in the oven so that the liquid sprayed pitch collected in the oven at any time will not cause undue chilling of the walls of the oven, and continuing the coking of collected residual matter to bring about shrinkage thereof to free coke from the side walls of the oven and to form a coke that is removable en masse from the oven by a pushing operation, and pushing the coke out of the oven.
